UNITED STATES PATENT OFFICE.

GEORGE F. DOWNS, OF BUFFALO, NEW YORK.

ROTARY FURNACE OR KILN.

1,381,096.

Specification of Letters Patent. Patented June 7, 1921.

Application filed June 19, 1920. Serial No. 390,242.

To all whom it may concern:

Be it known that I, GEORGE F. DOWNS, a citizen of the United States, and a resident of Buffalo, in the county of Erie and State 5 of New York, have invented certain new and useful Improvements in Rotary Furnaces or Kilns; and I do hereby declare that the following is a full, clear, and exact description thereof, reference being had to the 10 accompanying drawings, and to the letters of reference marked thereon, which form a part of this specification.

This invention relates to improvements in rotary furnaces or kilns adapted for roasting, sintering or like treatment of flue dust, iron ore and other concentrates and consists of the matters hereinafter described and more particularly pointed out in the appended claims.

20 The improved furnace or kiln is of the general type described in my prior Patents No. 1,121,906 of December 22, 1914, and No. 1,151,174 of August 31, 1915.

The furnace is cylindrical and is slightly 25 inclined downwardly from the feed end toward the discharge end and the flue dust or ore concentrates is subjected in its passage through the rotating furnace to heat, which is produced in the beginning by means of 30 fuel, either finely divided carbon or gas blown in at the discharge end of the furnace. In addition, the material is subjected to heat produced by the combustion of the finely divided carbon contained in it, so 35 that the ore is thoroughly heated, and caused to agglomerate into a sinter, in which form it is delivered from the discharge end of the furnace. From this sinter the metal 40 is finally recovered in another apparatus in a familiar manner.

In the course of the passage of the flue dust through the furnace, it is subjected to the action of blasts of air directed through twy whole which blasts not only provide the 45 air necessary for burning the carbon content of the flue dust, but in addition, act to scatter and violently agitate the material being treated, thus producing a continuous bombardment of the material in its passage 50 through the twyer area, or blast chamber of the furnace. This facilitates the mechanical union of the metallic or binder con-

tent of the material, while the chemical process of combustion provides the necessary heat to permit such mechanical union. 55

The improved kiln is provided with a novel form and construction of sintering or blast chamber designed to retard the travel of the material being treated through the kiln in the space or location where the actual sintering operation takes place. 60

The improved furnace is provided with means for collecting the heat from the sintered material as it is discharged from the furnace, which heat would otherwise be 65 wasted, and for making use of said heat to pre-heat the air supplied to the blast chamber.

It is sometimes found that the material to be sintered does not carry enough fuel to secure the proper amount of heat and to supplement this heat, I have provided an auxiliary fuel bin and fuel pipe in the neighborhood of the discharge end of the furnace which is adapted to discharge additional 75 fuel directly into the sintering chamber.

My invention also includes a novel construction, connection and mounting of the twyer and blast rings, whereby proper engagement is maintained by the two rings, 80 while at the same time the blast ring is permitted to have the necessary movement in the direction of the length of the furnace to accommodate the expansion and contraction 85 of the furnace.

The improved kiln or furnace has other novel features and advantages which will be pointed out more particularly as I proceed with my specification.

Referring now to the drawings:—

Figure 1 is a view of the discharge end of my improved rotary furnace, part in side elevation and part in longitudinal vertical section through the central axis of the furnace.

Fig. 2 is a view representing on an enlarged scale, a transverse section of the blast or twyer chamber, the plane of the section being indicated by the line 2—2 of Fig. 1.

Fig. 3 is a view representing on a like 100 scale, a transverse section through the furnace in the plane indicated by the line 3—3 of Fig. 1.

Fig. 4 is a view representing a longitudi-

nal section through the twyer or blast chamber in a plane indicated by the line 4—4 of Fig. 1.

Fig. 5 is a section through Fig. 3, on a 5 still further enlarged scale in a plane indicated by the line 5—5 of Fig. 3.

Fig. 6 is an enlarged, transverse section through the blast chamber in a plane indicated by the line 6—6 of Fig. 3.

10 Fig. 7 is a radial section through the blast ring, twyer ring and furnace wall, in a plane indicated by the line 7—7 of Fig. 3.

Fig. 8 is a detail elevation of part of the blast ring showing the grease grooves for 15 lubricating the twyer ring.

Fig. 9 is a developed longitudinal sectional view of the blast box.

Fig. 10 is an enlarged, longitudinal, sectional view of the discharge end of the blast 20 main.

Referring now to that embodiment of my invention illustrated in the drawings:—10 indicates the furnace proper which consists of a rotating cylinder lined on the interior with refractory material and mounted to rotate on supports, one only of which, 11, namely the one near the discharge end of the furnace, is shown. The supports as usual are provided with antifriction rollers 12. The cylinder has annular bands or rails 13 fixed to its outer surface and bearing upon the antifriction rollers 12 and is arranged to be rotatively driven in a familiar manner not shown. The discharge end of 30 the furnace is closed by the familiar hood 14. My improved furnace is provided with means adapted to make use of the waste heat of the sintered material, for preheating the air supplied by the blast main to 40 the blast or twyer chamber. 16 indicates the masonry which provides the support for the hood 14 and for the other apparatus located at the discharge end of the furnace. The pocket 15 in the hood is continued down into said masonry by a passage-way 17, which leads to a conducting pipe 18, having a flaring discharge end 19, which is located in the top of an upwardly inclined, rearwardly extending casing 20. Said casing provides a closed chamber in which is located an inclined, endless conveyer 21. The conveyer is in the form of a belt made of suitable material to resist the heat of the sintered material, which is discharged upon it by the pipe 18. It extends at each end, through suitable openings in the end walls of the casing 20, outside of which it is mounted on pulleys 22—22 supported in any convenient manner, the bottom lap being supported by transverse rods or rollers 23 located within the casing. The rear, higher end of the casing 20, which may be called the heat collecting chamber, is connected to a second casing 60 24, providing a heating or radiating chamber 65

in which are located a plurality of heating tubes 25 arranged in vertically spaced planes. Said casing is provided with an opening or outlet 26 at the top and with inlet and outlet passages 27—28 located in line with the heating tubes 25.

By this arrangement, the hot sintered material is discharged upon the conveyer belt 21 in the chamber 20 and in its passage on said belt through the said chamber, the heat 75 of the sintered material is given up and collected and then passes into the second chamber 24 where it is taken up by the heating tubes 25. The chamber 24 is interposed in the blast pipe (the inlet and outlets 27—28 80 forming part of said blast pipe) between the usual blower (not shown) and the discharge end 29 of said blast pipe. The air of the blast, as it passes in and about and between the hot pipes 25, is heated by radiation from 85 said pipes and in this way, the heat from the sintered material, which otherwise would be wasted, is used to preliminarily heat the blast supplied to the twyer or blast chamber.

90 In order to retard the flow of the material being treated in the blast or twyer area, the furnace cylinder is enlarged at or near its discharge end, as indicated at 30. In the embodiment of the invention illustrated, 95 said enlargement is provided by means of a radial, outwardly extending shoulder 31 and by a conical wall 32 offset from the diameter of the main length of the furnace, with its greater diameter at the shoulder 31 100 and its smaller diameter at the discharge end of the furnace.

The twyer pipes, instead of entering the furnace wall radially, as in my prior patents, are in the present instance parallel to 105 the longitudinal axis of the furnace and extend through openings in the radial wall 31 of the twyer chamber. 33 indicates the twyer pipes which are of the usual construction and are arranged in a circle as clearly 110 shown in Figs. 2 and 3. Said pipes are secured in a flat ring 34 which is arranged in a plane parallel to but spaced back of the radial shoulder 31 of the twyer chamber and open through the face of said ring remote 115 from said wall. The twyer pipes are made in two parts connected together by union fittings 33^a, so that the twyer ring may be disconnected when desired. 35 indicates a blast heat which is a second flat ring having 120 air-tight bearing engagement against the twyer ring 34 and provided in one part of its periphery with an arcuate, elongated box 36 which is made integral with said ring and provides the blast box.

125 The twyer ring 34 is supported by a plurality of radially extending brackets 37, symmetrically located about the body of the furnace and attached to the outside surface thereof,—the ring 34 being connected to said 130

brackets by a bolt and slot connection 38, as illustrated in Fig. 7, so as to be capable of radial adjustment with relation to the furnace. Each bracket is provided with a 5 horizontal ear 39 located adjacent to the inner periphery of the twyer ring 24 and adjusting screws 40, taking through said ears, provide for the necessary radial adjustment of the ring.

10 The blast ring 35 is supported on the twyer ring in a radial direction by means of a plurality of antifriction rollers 41 mounted on radially extending lugs 42, extending from the periphery of the twyer 15 ring. The blast ring is held in proper engagement against the face of the twyer ring by means of a plurality of arms 43 providing spindles for antifriction rollers 44, which engage the margins of the blast ring. The 20 arms 43 are bent at right angles to the axis of the rollers and extend through holes in radial extensions 45 of the twyer ring,—the necessary pressure being provided in each case, by a spring 46 which is interposed between the lug and a nut on the end of the 25 arm, as shown in Fig. 5. Each arm is held against rotation in its opening by means of a key 43^a. The arms and rollers 43—44 are arranged symmetrically about the rings, in 30 alternation on the inner and outer sides of said rings, as shown in Fig. 3. To provide the necessary lubrication between the rings, the blast ring has grease grooves 47 on its inner surface near its inner and outer peripheries,—(see Figs. 5 and 8), said grooves 35 having a plurality of branches 48 leading toward the median line of the ring, as shown in Fig. 8. The lubricant for said grooves is supplied by suitable grease cups 49 having inlets that extend through the blast ring 40 and enter into the bottom of the grooves 47—47. At one part of the blast ring is provided an elongated slot 35^a (see Fig. 3) which exposes two or more twyer openings 45 in the ring 34, so that the twyer pipes may be cleaned, when in the rotation of the furnace, they come into the area of said slot.

In the box 36 providing the blast box, 50 are located a plurality of spring-controlled valves 50, which are spaced apart distances equal to the distance between the twyer pipes. Said valves are adapted to close under the action of their springs against the 55 openings in the twyer ring communicating with the twyer pipes and their stems project beyond the box, through suitable stuffing boxes, where they are provided with handles 51 for withdrawing them against the action of their springs. Hand controlled triggers 60 52 are associated with the several valve stems for locking them in open position (see Fig. 6). By manipulation of these valves, the 65 number of twyer pipes to receive the blast may be controlled and adjusted to suit conditions.

In order to hold the blast spring 35 against rotative movement with the furnace and twyer ring, it is provided (as shown, in the neighborhood of the blast box) with a radial, depending anchor block 53, which 70 engages in a channel 54 of a bar 55,—the channel extending parallel to the length of the furnace. Said bar is rigidly mounted in any suitable manner, as for example, on I-beams 56, mounted on an upright support 75 or foundation 57 and rigidly connected by other beams 58 to the abutment 59 upon which the nearest main furnace support 11 is carried. By means of this construction, the blast ring is held against rotative movement, but at the same time is permitted to move in a longitudinal direction as the kiln 80 expands or contracts, also to follow any eccentric rotary movement of the kiln.

The blast pipe 29 near the kiln is supported and rigidly held by the beams 58. A flexible section 29^a connects this fixed part of the blast pipe with the blast chamber (see Fig. 1) the flexibility of this inlet part of the pipe accommodating the movement of 90 the blast ring in the expansion or contraction of the kiln (see Figs. 1 and 10).

60 indicates the usual fuel bin and 61 and 62 the usual blower and fuel pipe connected thereto, all being supported on the 95 masonry 16 at the discharge end of the furnace. In addition, there is provided an auxiliary fuel bin 63, and a fuel discharge pipe 64 connected therewith. The latter extends through the hood and is arranged 100 to discharge fuel by gravity directly upon the material being treated, as shown in Fig. 1. This auxiliary bin and fuel pipe are utilized when the material that is being sintered in the kiln does not carry enough 105 fuel to supply the required amount of heat.

The discharge opening of the furnace may be varied to suit conditions by means of a nose ring 65, which is supported on the discharge end of the kiln by a suitable flange 110 67. The discharge opening 67 may be varied by using nose rings having openings of different diameters.

It will be manifest that on account of the 115 enlargement of the kiln in the twyer area, the movement of the material being treated through the twyer area will be slowed down, thus giving more time to the sintering process. This slowing down is further increased by the converging shape of the wall of the 120 furnace toward the discharge opening which makes it necessary for the material in the bottom of the furnace to climb up an incline on its way to the discharge opening. The slowing down may manifestly be still 125 further effected by diminishing the diameter of the opening in the nose ring. Thus the time during which the sintering process is carried on in the twyer area, may be slowed down to suit all required conditions.

While in describing my invention, I have referred to certain details of mechanical construction and arrangement of parts, I do not wish to be limited thereto except as 5 may be pointed out in the appended claims.

I claim as my invention:

1. In a furnace of the kind described, a rotating cylinder, said cylinder being enlarged in the twyer area to provide a sintering chamber of diameter greater than the diameter of the rest of the furnace chamber. 10
2. In a furnace of the kind described, a rotating cylinder, said cylinder providing the furnace chamber and being constructed to retard the travel of the material, which is being treated, through the twyer area of the furnace chamber. 15
3. In a furnace of the kind described, a rotating cylinder, said cylinder being enlarged at or near its discharge end to provide a sintering chamber having its walls formed to retard the travel of material therethrough. 20
4. In a furnace of the kind described, a rotating cylinder, said cylinder having, toward the discharge end, a radial wall part extending outwardly from the main body of the cylinder, and an annular wall part connected thereto, converging toward the discharge end of the cylinder, said two wall parts providing an enlarged sintering chamber adapted to retard the flow of material therethrough. 25
5. In a furnace of the kind described, a rotating cylinder having a discharge end, said cylinder having an outwardly extending, radial wall part and a wall part which is tapered inwardly from said radial wall part toward the discharge opening and means for varying the diameter of the discharge opening. 30
6. In a furnace of the kind described, a rotating cylinder having a discharge end, said cylinder having an outwardly extending, radial wall part and a wall part which is tapered inwardly from said radial wall part toward the discharge opening, and a nose ring at said discharge end for determining the diameter of the discharge opening. 35
7. In a furnace of the kind described, a rotating cylinder, means providing a sintering chamber at the discharge end of the cylinder, said chamber being of a diameter at one end greater than that of the cylinder and being of substantially the diameter of the cylinder at its outer end which provides the discharge opening. 45
8. In a furnace of the kind described, a rotating cylinder, means providing a sintering chamber at or near the discharge end of the cylinder and means for discharging air into said sintering chamber in a direction parallel with the longitudinal axis of the cylinder. 50
9. In a furnace of the kind described, a rotating cylinder, means providing a sintering chamber at or near the discharge end of the cylinder, and means for discharging air into said sintering chamber in the direction of the travel of the material through the furnace. 70
10. In a furnace of the kind described, a rotating cylinder having a sintering chamber of greater diameter than that of the main body of the cylinder, said sintering chamber having a wall part extending radially outward from the cylinder body, a twyer ring spaced from said radial part and rotating with said cylinder, a plurality of twyer pipes connected to said ring and extending through said wall part, and a non-rotative blast ring engaged with said twyer ring, said blast ring having an elongated blast box which is adapted to communicate with the twyer pipes in succession as the cylinder is rotated. 75
11. In a furnace of the kind described, a rotating cylinder having a sintering chamber of greater diameter than that of the main body of the cylinder, said sintering chamber having a wall part extending radially outward from the cylinder body, a twyer ring spaced from said radial part and rotating with the cylinder, a plurality of twyer pipes connected to said ring and extending through said wall part, and a non-rotative blast ring engaged with said twyer ring, said blast ring having an elongated blast box adapted to cover a plurality of twyer pipe openings in the blast ring. 80
12. In a furnace of the kind described, a rotating cylinder having a sintering chamber of greater diameter than that of the main body of the cylinder, said sintering chamber having a wall part extending radially outward from the cylinder body, a twyer ring in a plane parallel to said wall part and spaced longitudinally therefrom, twyer pipes connected to said twyer ring and extending through said wall part, a blast ring engaged with said twyer ring, and means for holding said blast ring against rotation of the cylinder while permitting a movement thereof longitudinally of the cylinder. 105
13. In a furnace of the kind described, in combination with a rotating cylinder, a twyer ring surrounding the cylinder and located in a plane at right angles to the axis of the cylinder, a non-rotative blast ring engaged with said twyer ring and having an elongated blast box, a blast conduit having a flexible inlet connected to said blast box, and means for holding said blast ring against rotation but permitting a movement thereof longitudinally of the cylinder. 120
14. In a furnace of the kind described, in combination with a rotating cylinder, a twyer ring surrounding said cylinder and 125

5 rotatable therewith, said twyer ring being in a plane at right angles to the axis of said cylinder, a blast ring rotatively engaged with said twyer ring and having an elongated blast box, an anchor on said blast ring, means engaging said anchor adapted to lock the same against rotative movement but permitting movement in the direction of the length of the cylinder, a blast conduit, and a flexible blast inlet connecting said conduit with said blast box.

- therefrom, a casing providing a heating chamber about said conveyer belt, and means for providing a radiating chamber connected to said heating chamber at a point remote 5 from the receiving end of said conveyer, said radiating chamber being interposed in the length of said blast conduit.
26. In a furnace of the kind described, in combination with a rotating cylinder, the 10 blast head associated therewith and the blast conduit connected to said blast head, means for receiving and conveying away the material discharged from the said furnace, a casing providing a radiating chamber interposed in said blast conduit, and means for collecting the heat radiated from the discharged material and conducting it to said radiating chamber.
27. In a furnace of the kind described, 15 in combination with a rotating cylinder, the blast head associated therewith and the blast conduit connected to said blast head, means for conducting the fuel from the discharge end of said furnace to a point remote from 20 said discharge end, and means connected with said blast conduit for collecting the heat of the discharged fuel and supplying it to said blast conduit to pre-heat the blast of air passing therethrough.
28. In a furnace of the kind described, 25 in combination with a rotating cylinder, a twyer ring surrounding the cylinder and located in a plane at right angles to the axis
- of the cylinder, a non-rotative blast ring engaged with said twyer ring and having an 30 elongated blast box, a blast conduit having a flexible inlet connected to said blast box, and means for holding said blast ring against 35 rotation but permitting a movement of said blast ring in a direction longitudinal of the 40 cylinder and in a direction transverse of said cylinder.
29. In a furnace of the kind described, 45 in combination with a rotating cylinder, a twyer ring surrounding said cylinder and 40 rotative therewith, said twyer ring being in a plane at right angles to the axis of said cylinder, a blast ring rotatively engaged with said twyer ring and having an elongated blast box, an anchor on said blast ring, 50 means engaging said anchor adapted to lock the same against rotative movement but permitting movement in the direction of the length of the cylinder and in a plane at right angles thereto, a blast conduit, and a flexible 55 blast inlet connecting said conduit with said blast box.

In testimony that I claim the foregoing as my invention, I affix my signature in the presence of two witnesses, this 16th day of 60 June A. D. 1920.

GEORGE F. DOWNS.

Witnesses:

J. WUNSCH,
E. F. JULIUS.
